UNITED STATES PATENT OFFICE

159,180

LAWN SPRINKLER

William C. Wehner, Grosse Pointe, Mich., assignor to Wehner Engineering Company, a corporation of Michigan

Application January 22, 1949, Serial No. 397

Term of patent 14 years

(Cl. D91—1)

To all whom it may concern:

Be it known that I, William C. Wehner, a citizen of the United States and a resident of Grosse Pointe, in the county of Wayne and State of Michigan, have invented a new, original, and ornamental Design for a Lawn Sprinkler, of which the following is a specification, reference being had to the accompanying drawing, forming part thereof.

Fig. 1 is a front perspective view as seen from the left of a lawn sprinkler embodying my new design.

Fig. 2 is a front perspective view as seen from the right.

Fig. 3 is a front elevational view.

Fig. 4 is a rear elevational view.

Fig. 5 is a side elevational view as seen from the left of Fig. 3.

Fig. 6 is a side elevational view as seen from the right of Fig. 3.

I claim:

The ornamental design for a lawn sprinkler, as shown.

WILLIAM C. WEHNER.
